W. A. LORENZ

PAPER DRYING MACHINE

Filed Aug. 9, 1927

FIG. 1.

UNITED STATES PATENT OFFICE.

WILLIAM A. LORENZ, OF WEST HARTFORD, CONNECTICUT, ASSIGNOR TO THE OTAKA FABRIC COMPANY, OF HARTFORD, CONNECTICUT, A CORPORATION OF CONNECTICUT.

PAPER-DRYING MACHINE.

Application filed August 9, 1927. Serial No. 211,764.

This invention relates to machines for drying paper, and has particular application for drying paper which has been made elastic, such, for instance, as crinkled paper or 5 crinkled paper with longitudinal corrugations.

The aim of the invention is to provide a simple and effective machine by means of which elastic or crinkled paper may be economically dried without flattening or ironing out the crinkles.

Other objects will be in part obvious and in part pointed out more in detail hereinafter.

15 The invention accordingly consists in the features of construction, combination of elements and arrangement of parts which will be exemplified in the construction herein-after set forth and the scope of the application of which will be indicated in the appended claim.

In the accompanying drawings, wherein I have shown, for illustrative purposes, one of the many embodiments which the present 25 invention may take:

Figure 1 is a plan view of the apparatus with a web of paper passing therethrough, and

Fig. 2 is a sectional view taken substantially on line 2—2 of Fig. 1.

Referring to the drawings in detail, 30 10 designates generally a drying cylinder rotatably mounted on frames 11 and having a steam inlet pipe 12 and an exhaust pipe 13.

35 Passing about the cylinder is an endless belt 15 which is preferably porous. At opposite sides of the cylinder, the belt may be bowed away from the cylinder. For the purpose of guiding the bowed out parts, guide rolls 16 40 may be provided. The cylinder 10 may be driven in any suitable manner, as by means of a belt 17 passing about a pulley 18.

At the paper receiving side of the cylinder and between the cylinder and the belt 15 is a 45 vacuum box 20 which is more or less diagrammatically shown as it may be of any suitable shape or construction. The vacuum box has a blade or lip 21 which extends up into the angle between the belt and the cylinder, there being a slight space between the lip and cylinder. The vacuum box also has 50 a lower lip or blade 22 extending down into the angle between the cylinder and the belt where the belt leaves the cylinder. The blade

21 has such relation to the periphery of the 55 cylinder that air may be sucked through the belt into the box between the cylinder and the blade 21. The vacuum box has a pipe 23 leading to any suitable pump. If desired, there may also be provided a vacuum box 24 60 to the right hand side of the cylinder. This vacuum box is generally similar to the one 20 and has a like function.

The paper may be crinkled or longitudinally corrugated and crinkled in any suitable way. However, by way of example, I 65 have shown a corrugating and crinkling apparatus similar to that illustrated in my Patent No. 1,548,788, issued August 4, 1925. This apparatus is diagrammatically shown as having a pair of corrugating rolls 30 and 31 and a crinkling roll or cylinder 32 provided with teeth 33. The cylinder 32 is rotated at a lesser peripheral speed than the corrugated cylinder 31.

70 The operation of the apparatus is briefly as follows: The web of paper P passes between the rollers 30 and 31 where it is corrugated, as indicated at P', Fig. 1. It then passes between the cylinders 31 and 32 where 75 it is crinkled, as indicated at P'', Fig. 1. It is, of course, understood that that portion of the paper which is passing over the roller or cylinder 31 is corrugated throughout its width, and that the paper, after it passes 80 about the cylinder 32, is crinkled over its entire area. The paper passes from the cylinder 32 onto the endless belt 15 at a point adjacent the upper end of the blade or lip 21 of the vacuum box 20. The paper is carried 85 by the belt about the cylinder and over a guide roll 40 positioned beneath the vacuum box 20. Since the belt passes about the cylinder, and the cylinder is heated, the belt is also heated, with the result that the paper will 90 be quickly dried without flattening the crinkles. The vacuum boxes cause a vacuum 95 under the belt, and this vacuum will be of sufficient strength to hold the crinkled paper on the outside of the porous belt. Obviously, in case of thick papers, the web may be led about a succession of drying machines similar to that shown. The number of machines employed will depend upon the quality and thickness of the paper operated upon.

100 As many changes could be made in the above construction and many apparently widely different embodiments of this invention

tion could be made without departing from the scope thereof, it is intended that all matter contained in the above description or shown in the accompanying drawing shall

5 be interpreted as illustrative and not in a limiting sense.

It is also to be understood that the language used in the following claim is intended to cover all of the generic and specific features of the invention herein described and

10 all statements of the scope of the invention which, as a matter of language, might be said to fall therebetween.

I claim as my invention:

In a drying apparatus of the character described, a steam heated drying cylinder, an endless porous belt passing thereabout, and a vacuum box between said belt and cylinder for creating a vacuum beneath the belt.

WILLIAM A. LORENZ.
